WATER HEATER CONSTRUCTION

Walter S. Moffitt, Warwick, R. I., assignor to
General Fittings Company, Providence, R. I., a
corporation of Rhode Island

Application April 11, 1936, Serial No. 73,928

5 Claims. (Cl. 257—230)

My present invention relates to the heating art, and has particular reference to water heater constructions of the indirect type for domestic use.

5 It is the principal object of my invention to provide an indirect water heater construction which may be readily attached to any type of house boiler, and which will furnish an instantaneous supply of hot water for domestic purposes.

It is a further object of my invention to use a heater construction which eliminates the storage tank and the fittings normally required for the usual type of hot water installations.

15 An additional object of my invention is to provide an improved design for an indirect water heater which eliminates all possibility of air binding, and which is always completely filled with water moving in one direction.

20 A still further object of my invention is to provide an indirect heater construction which may be utilized with a circulating flow system, and without requiring a pump therewith.

Other objects of my invention are to provide a construction that can be thoroughly and quickly 25 drained for cleaning, or for winter layup, and which can be quickly restored to service whenever desired.

With the above and other objects and advantageous features in view, my invention consists 30 of a novel arrangement of parts more fully disclosed in the detailed description following, in conjunction with the accompanying drawing, and more specifically defined in the claims appended thereto.

35 In the drawing;

Fig. 1 is a side elevation of the novel water heater;

Fig. 2 is a front elevation of Fig. 1, parts being omitted for clearness;

40 Fig. 3 is a sectional view of the novel header construction on the line 3—3 of Fig. 2;

Fig. 3a is a sectional detail on the line 3a—3a of Fig. 2;

Fig. 4 is a perspective view of a header; and

45 Fig. 5 is a diagrammatic view showing the path of flow of water through the heater.

Referring to the drawing, the novel water heater 10 includes an outer shell or casing 11 which 50 has a boiler water inlet 12 at its upper end and a boiler water outlet 13 at its lower end, the casing having a front plate 14, see Fig. 2, in which a plurality of coils 15 are mounted, the coils being in the form of connected loops 16, preferably formed from a single length of copper tubing, and

having their ends 17 extending through inlet and outlet openings 18 and 18' respectively in the front plate 14, and swaged so as to be locked therein. The coils 15 are arranged vertically one above the other, but are inclined to each other at an angle to the horizontal, as indicated by the lines 19, see Fig. 5, whereby the flow therethrough is always in an ascending relation, as hereinafter explained. Two headers 20, 21, see Fig. 2, are mounted on the front plate 14, 10 as by bolts 22 extending through the headers and seated in cooperating threaded openings in the plate 14, flange 11' of the casing 11, the header 20 having an inlet opening 23 for water to be heated and an outlet opening 24 for heated water, the openings being threaded to receive piping nipples. Both headers have passageways or recesses 25, see Figs. 3a and 4, which serve to connect the ends of each coil 15 with the contiguous ends of the adjacent coil, as indicated in the diagrammatic Fig. 5, suitable packing of standard type being interposed between the headers and the front plate to ensure against leakage.

With the above described construction, the water to be heated enters the inlet 23, passes through the loops 16 of the first coil 15, always in an upwardly direction, then through the lowest recess 25 of the header 21 and into the next coil 15 which also is positioned so as to cause the flow to be continually upward, then through the lowest recess of the header 20, and so on until the outlet 24 is reached.

The inflow boiler water from a domestic heating plant or the like, enters through the inlet connection 12 and exits through the outflow connection 13, the flow of the boiler water around the coils of the water heater being continually in counter flow relation to the upwardly moving water in the water heating coils, whereby an extremely efficient transfer of heat from the boiler water to the domestic hot water supply is obtained.

The small cross-section of the heating coils and the very large surface area exposed to heat transfer relation with the hot boiler water produces a very rapid flow through the coils and a resultant rapid heating of the water, whereby a storage tank is not required. The continually upward flow of the water in the coils permits utilization of the heater in a circulatory system, as no air pockets can form, the flow through the piping being continuous, whereby opening a faucet immediately draws hot water from the system. Moreover, cleaning is facilitated, as removal of the headers exposes the ends of each

coil and drainage for cleaning and for summer layoff is positive.

It will be noted that the construction utilizes a small number of easily manufactured parts, 5 readily assembled and installed, whereby the cost of manufacture and of repair is low.

Although I have described a specific embodiment of my invention, it is obvious that changes in the form, sizes, and shapes of the parts to suit 10 different heating installation requirements may be made, without departing from the spirit and the scope of the invention as defined in the appended claims.

I claim:

15 1. In an indirect water heater, a casing having an inlet for heating fluid and an outlet for cooled heating fluid, said casing having a face plate, a plurality of substantially horizontal coils each comprising a plurality of continuous loops in the plane of the coil and in series and having its ends mounted in said face plate, and header means secured to said face plate and connecting said coils in series relation.

20 2. In an indirect water heater, a casing having an inlet for heating fluid and an outlet for cooled heating fluid, said casing having a face plate, a plurality of substantially horizontal coils each comprising a plurality of continuous loops in the plane of the coil and in series and having its ends 25 mounted in said face plate, and header means secured to said face plate and connecting said coils in series relation, the flow of heating fluid through said casing and of water to be heated through said coils being in counter relation.

25 3. In an indirect water heater, a casing having an inlet for heating fluid and an outlet for cooled heating fluid, said casing having a face plate, a plurality of substantially horizontal coils each 30

comprising a plurality of continuous loops in the plane of the coil and in series and having its ends mounted in said face plate, and header means secured to said face plate and connecting said coils in series relation, contiguous coils being in inclined relation, and the inlet to said coils being at the lower most point thereof, whereby water to be heated flows through the coils in continually ascending relation.

4. In an indirect water heater, a casing having an inlet for heating fluid and an outlet for cooled heating fluid, said casing having a face plate, a plurality of substantially horizontal coils each comprising a plurality of continuous loops in the plane of the coil and in series and having its ends 10 mounted in said face plate, and header means secured to said face plate and connecting said coils in series relation, the flow of heating fluid through said casing and of water to be heated through said coils being in counter relation, contiguous coils being in inclined relation, and the inlet to said coils being at the lower most point thereof, whereby water to be heated flows through the coils in continually ascending relation.

5. In an indirect water heater, a casing having an inlet for heating fluid and an outlet for cooled heating fluid, said casing having a face plate, and a plurality of substantially horizontal coils each comprising a plurality of continuous loops in the plane of the coil and in series, said 20 face plate having header means connecting said coils in series relation, contiguous coils being in inclined relation, and the inlet to said coils being at the lower most point thereof, whereby water to be heated flows through the coils in continually 25 ascending relation.

WALTER S. MOFFITT.
